UNITED STATES PATENT OFFICE.

CHARLES FRANCIS JENKINS, OF WASHINGTON, DISTRICT OF COLUMBIA, ASSIGNOR, BY
MESNE ASSIGNMENTS, TO SINGLE SERVICE PACKAGE CORPORATION OF AMERICA,
A CORPORATION OF NEW JERSEY.

TREATING PAPER BOTTLES.

935,848.

Specification of Letters Patent.

Patented Oct. 5, 1909.

Application filed June 25, 1908. Serial No. 440,368.

To all whom it may concern:

Be it known that I, CHARLES FRANCIS JENKINS, citizen of the United States, residing at Washington, in the District of Columbia, have invented certain new and useful Improvements in Treating Paper Bottles, of which the following is a specification, reference being had therein to the accompanying drawing.

Recently, paraffin-coated paper bottles have been used more or less extensively for milk, the intent being that no bottle shall be used but once. Practically, such bottles are useless if the cost exceeds a very low maximum, and it is nearly indispensable that the bottles be convenient, and quite indispensable that they be as perfectly sanitary as they can be made. These combined conditions make the production of satisfactory bottles difficult, and render every approach toward perfection, as well as the smallest reduction in cost, important.

I provide for waterproofing and sterilizing, without handling the bottles, by devices shown in the accompanying drawings, in which,

Figure 1 is a side elevation of the apparatus. Fig. 2 is an end elevation looking from the right in Fig. 1. Fig. 3 is a vertical section showing on a larger scale devices seen near the middle of Fig. 1. Fig. 4 is a partial enlarged view partly in section and corresponding nearly to a portion of Fig. 2. Fig. 5 is a plan view of devices seen also in Figs. 1, 2, 4. Fig. 6 is an enlarged plan view of devices seen near the left side of Fig. 1. Fig. 7 is a cross section of the correspondingly lettered tube of Fig. 1.

In these figures, A represents upright ends of a frame which are connected by four parallel rods B, B' the upper pair of which extend outward to any desired distance, being supported at their outer ends in any suitable way, as by standards C. In the main frame is supported a paraffin tank D heated by burners E, or the like, and in this is placed a downwardly curved tube D' which is upwardly open near its ends. Above the tube and its plane are mounted belt pulleys F carrying an endless belt F' provided at intervals with outwardly extending wings F² and having its

lower fold inside the tube D'. The belt is driven in any suitable way, as by a motor 55 G, belt G' and pulley G² on the shaft G³ of one of the pulleys F. Open cylindrical paper bottles H to be paraffined are placed in an inclined transverse chute I which delivers them in the open end portion D² of 60 the tube D' as shown in Figs. 2, 4, 5, the bottoms of the bottles being turned toward the body of the tube. The foremost bottle is caught by one of the wings F² and forced downward into the hot paraffin which enters 65 the tube through suitable openings D³ (Fig. 7), and as soon as the mouth of the bottle passes below the level of the liquid, the latter flows in expelling the air, which owing to the upward inclination of the bottle at 70 this time can never be imprisoned to prevent the liquid from reaching every part of the interior surface. As the advancing bottle rises, from the bath, toward the opposite end of the tube, all the paraffin is discharged. 75 The lower side of this end of the tube is bent downward at D⁴ (Fig. 3) and terminates in an inclined apron-like portion D⁵ terminating a little above a carrier belt K mounted upon pulleys K' driven in any 80 suitable way as by a belt K² from the motor, and supported by the rods B' which are connected by members B² to form a rigid frame. As the wings F² discharge the bottles upon the inclined apron the bottles 85 slide downward and gently tilt to erect position upon the conveyer belt which carries them through a sterilizing chamber M, of any desired length, which is highly heated by means of a gas burning device at N, 90 or by other suitable means. After leaving the sterilizer, they pass onward in the open air for such distance that the paraffin has time to cool and are finally discharged at the end of the conveyer.

To prevent possible accidents in feeding the bottles to the immersing tube, the foremost bottle in the chute rests against a light spring O, Fig. 5, which is pushed aside by the advancing wing which advances the bottle into the tube. This spring engages the bottle near its end so that the bottle usually tilts, as shown, so that the wing strikes the end squarely and moves the bottle in the direction of the axial line of the latter. If 105 for any cause the bottom of the bottle should

catch the edge of the chute at P, this edge yields, since the lower portion of this side of the chute is held in place by a light spring hinge Q and is readily swung out against an 5 inclined lip R upon the tube, the lip guiding the advancing bottle uninjured into the tube.

What I claim is:

1. The combination with a receptacle for liquid paraffin, of a conveyer adjacent 10 thereto, means for submerging open bottles in the paraffin and withdrawing and emptying them, and means for reversing and delivering the empty bottles in erect position to said conveyer.

15 2. The combination with a receptacle for paraffin and means for heating the paraffin therein, of a conveyer adjacent to said receptacle, means for submerging open bottles in the paraffin and withdrawing them with 20 their open ends downwardly inclined, and means for turning their open ends upward and delivering them in erect position to said conveyer.

25 3. The combination with a receptacle for paraffin and means for heating the same, of a sterilizing chamber, means for heating the chamber, a traveling conveyer arranged to carry material through said chamber, and automatic means for submerging open bottles in the paraffin, emptying them, and reversing and delivering them in erect position to said conveyer.

30 4. The combination with a receptacle for paraffin and means for keeping paraffin 35 therein in a liquid state, of an open way having its middle bent downward and submerged in the paraffin, an endless belt provided with wings and having one fold guided in said way, means for driving the belt, and 40 means for delivering an open bottle, with its axis parallel to the plane of said belt, in

front of each wing before the latter descends in said way.

5. The combination with a receptacle for paraffin, of an open way, in said receptacle, 45 having its central portion carried downward to submerge it in the paraffin, an endless belt provided with wings and having one fold guided in said way, means for driving the belt, and automatic means for delivering 50 a series of bottles to the advancing wings, respectively, with each bottle in position to have its end face met by its wing.

6. The combination with a chute adapted 55 to deliver a series of bottles placed transversely therein, of a transversely moving belt provided with wings in position to strike the ends, respectively, of the foremost bottles in the chute and remove them in succession, substantially as set forth.

60 7. The combination with an inclined chute, adapted for the descent therein of a series of transverse bottles, a transversely moving belt provided with wings in position to push the foremost bottles successively from the 65 chute, and a spring in position to limit the descent of the foremost bottle in the chute.

70 8. The combination with a chute adapted for guiding a series of bottles placed transversely therein, of means for moving the bottles of the series in succession laterally out of the chute, one guiding side of the chute being adapted to spring aside when pressed by an outgoing bottle, substantially as set forth.

In testimony whereof I affix my signature in presence of two witnesses.

CHARLES FRANCIS JENKINS.
